Ira H. Blessing

UNITED STATES PATENT OFFICE.

IRA H. BLESSING, OF ALBANY, NEW YORK.

TELEGRAPHER'S FINGER-GUARD.

SPECIFICATION forming part of Letters Patent No. 681,185, dated August 27, 1901.

Application filed November 14, 1900. Serial No. 36,431. (No model.)

To all whom it may concern:

Be it known that I, IRA H. BLESSING, a citizen of the United States, residing at Albany, New York, have invented certain new and useful Improvements in Telegraphers' Finger-Guards; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

The object of my invention is to provide a new and improved finger-guard for telegraphers.

In the drawings, Figure 1 shows a plan view of one form of my guard; Fig. 2, a longitudinal sectional view thereof; Fig. 3, an equivalent therefor, showing the same in side elevation; Fig. 4, a top plan view of Fig. 3; and Fig. 5, a side elevation of a telegraphic button and a similar view of that form of my invention shown in Fig. 1 as used in connection therewith, a hand being shown in the dotted lines in the ordinary position when using a telegraphic instrument.

The main disadvantage experienced in using the ordinary telegraphic instrument as it is commonly used is that the button 8 is grasped between the thumb and the side of the second finger 4, as seen in Fig. 5. The constant vibratory motion given the button 8 and the pressure against the side of finger 4 cause the button to press into the flesh and make the finger first sore and then calloused and finally results in lameness and soreness of the hand, wrist, and arm, ending many times in what is called "telegraphers' paralysis." To avoid this pressure on the finger and to mitigate the action of this vibratory motion on the muscles of the finger, hand, and arm, I have devised a ring 1, having a hole 2 for the insertion of the finger 4, which is the second finger of the hand, and on the surface of the hole I have preferably formed a soft surface or cushion by buffing or raising said surface, as seen at 3; but any sort of cushioning material may be attached to said surface, if preferred, such as velvet or plush or any other desired material, or if the material of which the ring 1 is formed is itself soft and pliable no

cushioning may be had, if desired. I preferably make my ring 1 of rubber or leather, and preferably make the hole 2 eccentric with the body of the ring; but any material desired may be used and the hole be made central, if desired, and the ring made to stay in place on the finger by any other means than the hole 2, as will at once be evident to those skilled in the art; but I prefer it as shown.

When the form shown in Fig. 1 is used, it is slipped on the finger, as seen at 1 in Fig. 5, when it will rest upon the top edge of the button 8, and the side of the finger 4 may be held so as not to touch the edge of the button 8, and the finger will be relieved of the pressure of the button, and the bearing of the inner surface of the hole will be entirely around the whole surface of the finger and so thus distributed that the nerves of the finger are not affected disadvantageously, and telegraphing will be found to be much easier and less fatiguing, and there will be no pains in the hand, wrist, or arm after protracted work with the instrument. When that form of my device shown in Figs. 3 and 4 is used, the same result is attained, and it is an equivalent of that form seen in Fig. 1. The numerals 5 and 6 show loops encircling the finger 4, made by looping a piece of wire at each end and having a shank and a projection 7, all forming, preferably, one instrument. The finger 4 is slipped into the top loop and down into the bottom loop 6, and as the projection 7 projects from the side of finger 4 and the wire is more or less flexible the finger is easily bent while the guard is in position, the projection 7 resting on top of the button 8 precisely as does the ring 1, as seen in Fig. 5.

In the form shown in Fig. 3 there are two bearings against the finger, as seen at 5 and 6, which relieve any undue pressure upon the finger at any one spot or small area of its surface, and thus no injury is done the finger, and the nerves are almost entirely relieved of any tendency to being overworked or otherwise injured. It will be evident to those skilled in the art that there can be made a number of modifications of this form of the device which will act as equivalents thereof without departing from the spirit of my invention, and I therefore declare that I do not confine myself to the exact form shown either

of the ring 1 or of the wire device shown in Figs. 3 and 4, but claim all equivalents thereof.

Where the loops 5 and 6 or the ring 1 is made of wire or other bendable material, it will be found that by simply contracting or spreading the loops they may be made to fit almost any ordinary finger, and therefore such loops are adjustable to various fingers, and I therefore claim such as being adjustable guards, the adjustability thereof being a feature in the device.

I do not confine myself to any particular manner of holding the device to the finger, as it may be done by the loops shown or in any other desirable way, such as will be readily perceived.

The operation is as follows: When the device is in position on the finger, as shown, the projecting edge of ring 1 or the projection 7 (seen in Figs. 3 and 4) will rest in contact with the key-button 8, as seen. As the hand is pressed down the projection forces the button 8 down and it is brought back partly by the spring always used in connection with such instruments and partly by the thumb, the finger 4 having nothing whatever to do with bringing the button back to its normal condition, as the finger 4 itself does not touch the button 8 when wearing my guard. In this way the edge of the button does not press into the finger, making an indent therein, as is the case when my guard is not worn, nor

does the button nor my device irritate the finger or its nerves, it being easily possible to work a telegraphic instrument continuously all day without feeling the usual fatigue experienced with an instrument when not using my guard. Those who have contracted partial paralysis by long work with the telegraphic instrument can by wearing my guard operate as well as ever, provided the whole arm is not paralyzed.

Now, having fully described my invention, so that those skilled in the art may know how to make and use the same, I declare that what I desire to secure by Letters Patent is—

1. A finger-guard for telegraphers consisting of a body carried on the finger, a portion of said body projecting outwardly and arranged to lie on or overlap the telegraph-key in order that the downstroke of the key shall be made by the pressure of the projection on the key substantially as described.

2. As a new article of manufacture a finger-guard for telegraphers consisting of a body carried on the finger, a portion thereof projecting outwardly and arranged to overlap the telegraph-key substantially as described.

In testimony whereof I affix my signature in presence of two witnesses.

IRA H. BLESSING.
